UNITED STATES PATENT OFFICE.

GEORGE A. ARNOLD, OF BOSTON, MASSACHUSETTS, ASSIGNOR OF ONE-HALF TO
FREDERICK C. HERSEE, OF BOSTON, MASSACHUSETTS.

EYEGLASSES.

1,195,826.

Specification of Letters Patent. Patented Aug. 22, 1916.

Application filed October 16, 1915. Serial No. 56,197.

To all whom it may concern:

Be it known that I, GEORGE A. ARNOLD, a citizen of the United States, and a resident of Boston, in the county of Suffolk and 5 State of Massachusetts, have invented certain new and useful Improvements in Eye-glasses, of which the following is a specification.

This invention relates to certain improvements in eye-glasses and has for its object 10 the provision of simple, inexpensive and easily operated means for shading the eyes from bright or glaring lights.

The eye-glasses constructed in accordance 15 with my invention are primarily useful to automobilists to protect the eyes from the sun, search lights on other cars, or other bright lights, although they may also be used in various industries in which very 20 bright lights, or illuminated objects or bodies are employed.

In my improved construction, the eye-shade is of transparent material and of such character that it will intercept certain of 25 the light rays and so positioned that it may be readily brought into or out of the line of vision.

As an important feature of my invention, I so design the shade and its support that 30 it may be readily attached to the ordinary eye-glasses now in use. The body portion of the shade may be made of colored glass, celluloid, or other like material and the support for the shade preferably includes a 35 pivotal connection to a clamp adapted to grip the lenses or frame of the eye-glasses.

Reference is to be had to the accompanying drawings in which I have illustrated two embodiments of my invention and in which 40 similar reference characters indicate corresponding parts in the several views.

In these drawings, Figure 1 is a front elevation of a device constructed in accordance with my invention and applied to a 45 pair of eye-glasses; Fig. 2 is a top plan view of the construction shown in Fig. 1, a portion thereof being shown in section and the shade being shown in dotted lines in raised position; Fig. 3 is a transverse section on 50 the line 3—3 of Fig. 1; Fig. 4 is a front elevation of a modified form; and Fig. 5 is a transverse section on the line 5—5 of Fig. 4.

I have illustrated my invention as applied to a pair of spectacles having large round

lenses 10 supported in a frame 11, the latter having pivoted side bows 12. The frame and bows may be of metal, celluloid, imitation tortoise shell or any other suitable material. I do not desire to be limited in any way to the particular type of eye-glasses to which my invention is here applied as it may be used on those forms in which the lenses are directly connected to the bridge piece and in which there are no side bows or frame around the lenses. It may also be applied to various forms of goggles which may be considered merely as one form of eyeglasses.

In the specific form shown in Figs. 1, 2 and 3, the eye-shade is in the form of a piece 70 of celluloid 13 cut to form two circular portions 14 and a connecting portion 15. The shade is of such size and so designed that when in operative position, the circular portions 14 come substantially concentric with 75 the main lenses and at a slight distance in front of the latter. The circular portions of the shade are preferably somewhat smaller than the lenses so that they do not cover the entire area of the latter. This permits the 80 wearer to look through the lower portions of the lenses without looking through the shade if he desires. The lower part of the shade may be cut away so as to expose a larger portion of the lenses if desired. 85

For connecting the shade to the eye-glasses and permitting of the desired movement of the shade into and out of operative position, I provide a clamping member 16 adapted to resiliently engage with and be 90 retained by the eye-glasses. This clamp is shown in the form of a strip of sheet metal bent to form an inverted channel into which the upper edges of the frames of the two lenses may be inserted. The side walls of 95 the channel are sufficiently resilient so that they grip the frame and may be retained in place, but at the same time may be removed when desired. The clamp forming strip at its ends has two forwardly and upwardly extending ears or flanges 17 serving as the support for a transverse rod or bar 18 disposed substantially parallel to the clamp member and mounted to rotate about its own axis in these flanges. 100

The shade is rigidly secured to the center portion of this bar so as to swing about the axis of the latter upon the rotation of the 105

bar. The shade may be secured in various different ways, but as shown the center portion of the bar is made of two parallel strips between which the sheet of celluloid extends and a plurality of pins hold the two strips and the sheet together.

For rotating the pivot rod and thus swinging the shades into or out of the line of vision, I provide two collars 19 and 20 upon opposite sides of one of the supporting flanges 17. These may engage friction tight with the opposite surfaces of the flange and one of the collars, for instance, the outer collar 20, may serve as a knob by which the pivot rod may be rotated. The frictional engagement of the collars with the flange will serve to hold the rod in any desired rotated position.

If desired, I may provide auxiliary friction means in the form of a coil spring 21 set in a recess in one of the collars and having its opposite ends abutting against the flange and the base of the recess in the collar. The spring, being under compression, will give the desired resistance to the rotation of the rod. The shade, when in operative position, will be in the line of vision in front of the lenses as shown in Figs. 1 and 3, but when the shade is unnecessary, it may be raised to the position indicated in dotted lines in Figs. 2 and 3 and may then be out of the line of vision.

By making the shade of celluloid and the parts of thin metal as illustrated, the shade will add very little weight to the glasses and for that reason may be left on the glasses at all times, but on cloudy days or when the wearer is not in the presence of glaring lights, he may, very readily remove the clamp from the upper edge of the frame, thus restoring the glasses to their original position. The removed frame and shade may be carried in the pocket ready for use when desired.

The shade is shown in Figs. 1, 2 and 3 in the form of a single piece of sheet celluloid. This may be green, brown, amber or any other color, selected in accordance with the character of the light from which the user desires to protect his eyes.

The cutting of the shade from a single piece of celluloid with the eye portions 14 and the connecting portion 15, makes the said eye portions substantially rigid in respect to each other. If desired, the connecting portion 15 may be entirely omitted and the eye portions 14 connected directly to the pivot bar. In such a construction, the eye portions of the shade might be adjusted toward and from each other to adapt them to the distance between pupillary centers of the glasses to which the shade is applied. This adjustment is possible in the construction illustrated in Figs. 4 and 5. Here, I form the shade of eye-pieces 25 of glass mounted

in suitable frames 26. These eye-pieces may be of the same size as the lenses of the glasses or they may be smaller if desired. As shown, the frame 26 of each eye-piece of the shade has an upwardly extending lug 27 adapted to be held within a clamp 28 on the pivot rod. Each clamp is formed of sheet metal bent to present two substantially parallel gripping portions for engagement with opposite sides of the lug and held together by a screw 29. The clamps may be adjustable along the pivot rod 18^a or the eye-pieces may be swung toward and from each other about the screws 29 as centers to bring the centers of the eye-pieces into line with the centers of the lenses. The pivot rod 18^a is illustrated as being supported and rotated by substantially the same construction as that shown in Figs. 1, 2 and 3.

Although my device is primarily intended as a shade for the eyes, yet it is evident that the eye-pieces, particularly in the forms shown in Figs. 4 and 5, need not be colored and may be lenses of such power that when in the line of vision and in combination with the main lenses, will convert the eye-glasses from distance glasses to reading glasses.

Having thus described my invention, what I claim as new and desire to secure by Letters Patent is:

1. The combination with a pair of eye-glasses including lenses, of a clamp adapted to detachably engage with the latter, a pivot rod having its axis in a plane substantially parallel to the plane of said lenses and supported by said clamp, and an eye-shade carried by said pivot rod.

2. The combination with a pair of eye-glasses, of a substantially U-shaped clamp adapted to frictionally engage with said eye-glasses and be retained thereon along a line substantially tangent to the upper edges of the lenses of said eye-glasses, and an eye-shade pivotally connected to said clamp.

3. The combination with a pair of eye-glasses, of a substantially U-shaped clamp adapted to frictionally engage with said eye-glasses and be retained thereon along a line substantially tangent to the upper edges of the lenses of said eye-glasses, and a transparent member pivotally connected to said clamp and movable into and out of the line of vision of the eye-glasses.

4. The combination with a pair of eye-glasses, of a clamping member adapted to frictionally engage with and be retained by said eye-glasses along a line substantially tangent to the lenses above the latter, a pivot rod carried by said clamping member and substantially parallel thereto, and an eye-shade carried by said pivot rod.

5. In combination, a substantially channel-shaped member adapted to receive portions of the frame of a pair of eye-glasses between the side flanges thereof and having

outwardly extending lugs or ears at its ends, a pivot rod supported in said lugs or ears, and eye-pieces carried by said pivot rod.

6. In combination, a substantially channel-shaped member adapted to receive portions of the frame of a pair of eye-glasses between the side flanges thereof and having outwardly extending lugs or ears at its ends, a pivot rod supported in said lugs or ears, 10 and colored transparent eye-pieces carried by said pivot rod and movable into or out of the line of vision of the eye-glasses.
7. In combination, a substantially channel-shaped member adapted to receive portions of the frame of a pair of eye-glasses between the side flanges thereof and be frictionally retained thereon, and having outwardly extending lugs or ears at its ends, a pivot rod supported in said lugs or ears, and 15 colored transparent eye-pieces carried by said pivot rod and movable into or out of the line of vision of the eye-glasses.
8. An attachment for eye-glasses including a clamping member adapted to be secured to the glasses along the upper edge of the lenses, a pivot rod carried by said clamping member and substantially parallel thereto, and a piece of colored sheet celluloid carried by said pivot rod and movable into or out of the line of vision of the eye-glasses.

9. An attachment for eye-glasses including a clamping member adapted to be secured to the frame of the glasses, a pivot rod carried by said clamping member and substantially parallel thereto, and colored sheet celluloid eye-pieces carried by said

pivot rod and movable into or out of the line of vision through the lenses of the eye-glasses.

10. An attachment for eye-glasses, including a clamping member adapted to be secured to the eye-glasses, a colored sheet celluloid eye-shade, and pivotal connections between said eye-shade and said clamping member.

11. In combination, a member adapted to engage with and be retained by a pair of eyeglasses along the upper edge of the lenses and having outwardly extending lugs or ears, a pivot rod supported in said lugs or 50 ears and having its axis in a plane substantially parallel to the plane of the lenses and colored transparent eye-pieces carried by said pivot rod and movable into or out of the line of vision of the eyeglasses.

12. An attachment for eye-glasses including a clamping member adapted to be secured to the glasses along the upper edge of the lenses, a pivot rod carried by said clamping member and substantially parallel thereto and having a slot extending lengthwise thereof, and a piece of colored sheet celluloid extending through said slot and carried by said pivot rod and movable into or out of the line of vision of the eye-glasses.

Signed at Waltham in the county of Middlesex, and State of Massachusetts this thirteenth day of October, A. D. 1915.

GEORGE A. ARNOLD.
